UNITED STATES PATENT OFFICE.

GILBERT WAYNE RUGGLES, OF YOUNGSTOWN, OHIO.

STOKER RAM.

Application filed November 26, 1920. Serial No. 426,341.

To all whom it may concern:

Be it known that I, GILBERT WAYNE RUGGLES, a citizen of the United States, and a resident of Youngstown, county of Mahoning, and State of Ohio, have invented a new and useful Improvement in Stoker Rams, of which the following is a specification, the principle of the invention being herein explained and the best mode in 10 which I have contemplated applying that principle, so as to distinguish it from other inventions.

My invention consists of an apparatus for feeding or ramming material, which is so 15 constructed as to be protected against breaking pressure. More particularly, it comprises a stoker ram for furnace feeding having a main ram and an auxiliary ram so associated that when excessively hard or 20 compacted material is encountered a connecting piece will fail or fracture and release the large or main ram from the driving connections, without interfering with the continued operation of the smaller auxiliary ram which thereafter serves to relieve 25 the conditions causing such fracture.

Heretofore, apparatus of this character has been injured when foreign matter in the material being fed has been encountered, 30 or, when safety means has been provided the entire ramming apparatus has been released from operation.

Among the objects of my invention are the provision of improved means for relieving the apparatus from dangerous strains or 35 breakage, due to excessive pressure, the provision of an auxiliary device which may continue to operate after the main compressing or feeding element has been released, and the provision of a novel construction of safety means for apparatus of 40 this character. To the accomplishment of the foregoing and related ends, said invention, then, consists of the means hereinafter 45 fully described and particularly pointed out in the claims.

The annexed drawing and the following description set forth in detail certain mechanism embodying the invention, such 50 closed means constituting, however, but one of various mechanical forms in which the principle of the invention may be used.

In said annexed drawing:—

Fig. 1 is a longitudinal sectional view 55 showing the manner in which my improved ram mechanism may be applied to a fur-

nace having a fuel hopper feeding to an inclined grate; Fig. 2 is a longitudinal vertical section showing the details of the ram or feeding structure of my device; Fig. 3 is a plan view of the parts enclosed within the main ram illustrated in Fig. 2, the main ram walls being shown in section; Fig. 4 is a transverse vertical section along the line 4—4 shown in Fig. 2, looking in the direction of the arrows; and Fig. 5 is an end view of the outwardly facing portion of the ram.

As is shown in Fig. 1, the ram mechanism 1 is interposed between the hopper 2 and the inclined grate 3 of a furnace, the front wall 4 of which is indicated in the drawing. Obviously, its position with respect to furnaces or apparatus of other construction could be varied as desired. The details of the ram structure are more clearly shown in 75 Figs. 2 and 3. The main ram 5 comprises a hollow cylindrical member 6 provided with a wall 7 at one end and with an inner annular shoulder 8 near its other end. The shoulder is formed by making the rearward 80 diameter of the ram cylinder slightly larger than the main portion thereof. Adjacent the shoulder upon the inner portion of said cylinder a plurality of integral lugs 9 are provided which are apertured to receive 85 the screw threaded ends of bolts 10. The end wall of the main ram cylinder is formed with an aperture 11 preferably in a position 90 slightly below its center and for the greater portion of its lower longitudinal central extent has a slot 12 for a purpose hereinafter to be explained. A slot 13 of less extent is 95 also formed in the upper wall of the cylinder. A pair of half heads 14 of a vertical diameter approximately equal to the largest 100 diameter of the cylinder are secured against the annular shoulder 8 heretofore mentioned by means of a plurality of bolts which engage the lugs 9 heretofore described. As is shown in Fig. 5, the pair of half heads 14 are spaced from each other centrally to allow free passage for the operating arm of a lever described in detail hereinafter. Each of the half heads is provided near its upper central inner edge with a rearwardly 105 extending projection 15. The upper end of each of said projections is notched to provide a horizontal supporting face 16 and a vertical rearwardly facing shoulder 17 thereon. Within the cylinder adjacent its side portions are provided two slide rods 18, 110 the ends of which are of reduced diameter

and seated within apertures 19 in the front wall of the cylinder, while the rear ends thereof are seated in apertures 20 within the respective half heads. A cross head 21 of irregular formation is positioned centrally of the cylinder and carries on a vertical face 22 at its inner end an auxiliary ram 23, the front end of which passes through the aperture 11 in the front wall 10 of the cylinder and extends slightly therebeyond.

The ram body proper may be connected to the cross head 21 by means of an aperture and a swaged or up-set end 24, as is shown 15 in Fig. 2. The rearward portion of the cross head has a vertical slot 25 on its under side and centrally of the two walls 26 thus provided, a pair of aligned bearings 27 are formed. The upper face of the cross head 20 is provided with a channel-way 28 extending longitudinally of the central upper portion and has an enlargement 29 at its forward end so as to provide for engagement 25 with a link member 34 having a T-shaped head on each end, described in detail hereinafter. At each side of the cross head 21 a grooved lug 30 is provided, of a size to slidably engage the slide rods heretofore described. Within the bearings provided in 30 the cross head 21 a pivot pin 31 is positioned. An operating member or crank pin 32 upon a drive shaft positioned adjacent the ram has pivoted thereto a bell-crank lever 33, which extends within the cylinder and has 35 its angle part journaled upon the pin 31 in the cross head. The slots 12 and 13 in the cylinder permit the free motion of the bell-crank lever 33, the lower end of which operates other mechanism.

40 A link member 34 of relatively frangible material comprising a narrow longitudinal central portion having laterally extending ends which form T-heads on each end serves as the connecting means between the cross head just described which carries the auxiliary ram and the half heads which are fixed to the body of the main ram cylinder. The head 35 at the forward end of the link member is shown as of a size to engage with 45 the channel portion of the cross head of the auxiliary ram and the head 36 of the rearward portion as of a size sufficient to bridge the space between the half heads and engage with the vertical shoulders provided on 50 the projections on said half heads. As shown in Fig. 3, the link is provided with an aperture 40 near the head 36, in order to have the failure of the link occur at this point where the parts are more accessible for 55 removal and replacement. The size of the aperture may be varied so as to have the link fail under any desired amount of tension.

60 The operation of the device is as follows:—

65 The entire ram assembly is reciprocated

by means of the bell-crank lever and intermittently comes into contact with the fuel fed through the hopper gate, and forces it upon the inclined grate. The contact end of the ram assembly, by reason of the inside 70 or auxiliary ram extending through and projecting slightly from the wall portion of the main ram, presents an irregular surface designed to leave a depression in the fuel in front of the ram. Should foreign matter be encountered in the material operated upon, or an excessive degree of pressure caused for any other reason, the link member will fail because of its special construction. Inasmuch as the link is the only 75 driving connection between the main ram and the auxiliary ram during the forward or feeding movement, the main ram will thus be released from the operating means while the auxiliary ram will continue to be reciprocated sliding on the rods provided within the main ram cylinder. It will be understood that the return movement of the main ram is effected in any case by the direct engagement of the reciprocatory head 21 with the so-called half heads 14 fixedly secured in the rear portion of said main ram; in other words, the frangible link 34 is not necessarily or desirably used in such return movement. The auxiliary ram being of smaller 80 diameter than the main ram, it will be able to dislodge the material packed before it and in a measure will continue to supply fuel to the grate until such time as the link can be replaced and the entire apparatus brought 85 back into normal operation.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In an apparatus for feeding material, the combination of two ram members having contiguous faces adapted to engage with and push the material to be fed, means for reciprocating one of said members, and means interconnecting said members so as to render same conjointly operable, said means permitting one of said members to become inoperative under abnormal conditions.

2. In an apparatus for feeding material, the combination of two ram members having contiguous faces adapted to engage with and push the material to be fed, such operative face of one member being of considerably smaller area than that of the other, means for reciprocating the member having the face of smaller area, and means interconnecting said members so as to render same conjointly operable, said means permitting the member having the face of larg-

er area to become inoperative under abnormal conditions.

3. In an apparatus for feeding material, the combination of two ram members having contiguous faces adapted to engage with and push the material to be fed, means directly connected with one of said members for reciprocating the same, and a frangible element operatively interconnecting said members so as to render the same normally conjointly operable.

4. In an apparatus for feeding material, the combination of two ram members having contiguous faces adapted to engage with and push the material to be fed, means directly connected with one of said members for reciprocating the same, and a frangible element operatively interconnecting said members so as to render the same normally conjointly operable, said element being arranged and constructed so as to be under tension during the feeding movement of said members.

5. In an apparatus for feeding material, the combination of two ram members having contiguous faces adapted to engage with and push the material to be fed, such operative face of one member being of considerably smaller area than that of the other, means directly connected with one of said members for reciprocating same, and a frangible link operatively interconnecting said members, said link being arranged and constructed so as to be under tension during the feeding movement of said members.

6. In an apparatus for feeding material, the combination of two ram members having contiguous faces adapted to engage with and push the material to be fed, such operative face of one member being of considerably smaller area than that of the other, means directly connected with one of said members for reciprocating same, and a detachable frangible link operatively connecting with said members, said link being arranged and constructed so as to be under tension during the feeding movement of said members.

7. In an apparatus for feeding material, the combination of two ram members having contiguous faces adapted to engage with and push the material to be fed, such operative face of one member being of considerably smaller area than that of the other, and said members being formed with recesses, means directly connected with one of said members for reciprocating same, and a frangible link formed with enlarged ends detachably engaging such recesses.

8. A stoker ram apparatus comprising a guide-way, a main ram reciprocable therein, said main ram being formed of a hollow member provided with an apertured wall at its forward end, an auxiliary ram having

ture in said main ram, and a frangible driving connection between said main ram and said auxiliary ram, upon failure of which, said auxiliary ram is permitted to operate through such aperture in such main ram.

9. A stoker ram apparatus comprising a guide-way, a main ram reciprocable therein, said main ram being formed of a hollow member provided with an apertured wall at its forward end and with longitudinally extending internal guides, an auxiliary ram supported on said guides and having its forward end extending through such aperture in said main ram, and a frangible driving connection between said main ram and said auxiliary ram, upon failure of which, said auxiliary ram is permitted to operate through such aperture in such main ram.

10. A stoker ram apparatus comprising a guide-way, a main ram reciprocable therein, said main ram being formed of a hollow member provided with an apertured wall at its forward end, parallel slide rods within said member and a fixed head near the rear end thereof, an auxiliary ram supported on said slide rods and having its forward end extending through such aperture in said main ram, said auxiliary ram being adapted to engage with said fixed head in said main ram to retract the same, and a frangible driving connection between said main ram and said auxiliary ram for advancing the former, said auxiliary ram being permitted to operate through the opening in the wall of said main ram upon failure of such connection.

11. In an apparatus for feeding material, the combination of a ram member, a reciprocatory cross-head within said member, said cross-head being adapted directly to engage with said member to retract same; and a frangible element interconnecting said member and cross-head, said element being arranged so as to be under tension during the feeding movement of said member and constructed to break under a predetermined strain.

12. In an apparatus for feeding material, the combination of a ram member, a reciprocatory cross-head within said member, said cross-head being adapted directly to engage with said member to retract same and said cross-head and member being formed with recesses, and a frangible link formed with enlarged ends detachably engaging such recesses, said link being arranged so as to be under tension during the feeding movement of said member and being constructed so as to break under a predetermined strain.

Signed by me, this 22nd day of November, 1920.

GILBERT WAYNE RUGGLES
